[57] CLAIM

The ornamental design for a floor outlet housing with sliding closures, as shown and described.

DESCRIPTION

FIG. 1 is a front, top and one side perspective view of the floor outlet housing with sliding closures showing my new design;

FIG. 2 is a rear, top and opposite side perspective view thereof, the bottom being plain and unornamented;

FIG. 3 is a top plan view thereof with the sliding closures shown in the open position.

The broken line showing of the receptacle outlets in FIG. 3 is for illustrative purposes only and forms no part of the claimed design.

FIG. 1.

FIG. 2.

FIG. 3.
